UNITED STATES PATENT OFFICE

ABRAHAM SPRUNG, OF NEW YORK, N. Y., ASSIGNOR TO MUNICIPAL STREET SIGN CO., INC., OF NEW YORK, N. Y., A CORPORATION OF NEW YORK

YIELDABLE TRAFFIC BARRIER

Application filed May 28, 1929. Serial No. 366,587.

This invention relates to safety devices as used to divert vehicular traffic from restricted areas, safety zones and like localities where driving is interdicted.

5 Near the intersections of streets, on one or both of which are tracks for street cars, there are provided landing stations where the cars stop to receive and let off passengers who would be subjected to hazards while standing adjacent the track, except that the rule is that vehicles must pass outside a defined safety zone, sometimes marked at its ends by a single safety staff, with or without a light at night.

15 It is the purpose of the present invention to provide an efficient barrier for such safety areas, that is plainly visible and of such width as to effectively deter drivers from bringing vehicles into contact with it.

20 A further feature is in the provision of a sign bearing legends at the top of the supporting post, and also a plurality of brilliants on the barrier elements capable of reflecting the light from an approaching vehicle backward to the driver who is thus warned of its 25 imminence, causing a detour or stoppage.

Another advantageous object is to arrange the wing-like side elements of the barrier in the manner of a pair of yieldable gates, pivoting on the post in either direction quite independently, and to provide means for their automatic return to normal extended position should either be displaced.

These important objects, together with others, such as a pleasing, graceful appearance, due to its symmetrical design, strength and moderate cost of construction, are accomplished by the novel construction, arrangement and combination of parts hereinafter described and illustrated in the accompanying drawing, forming a material part of this disclosure, and in which:

Figure 1 is a side elevational view of an embodiment of the invention as operatively extended.

Figure 2 is a vertical sectional view taken on line 2—2 of Figure 1.

Figure 3 is a fragmentary side view taken at a right angle to Figure 1 and showing one

of the gate elements swung into an inoperative position.

A block of concrete 10, preferably firmly embedded in the street in an appropriate position, has set centrally in it an upright tubular post 11 to extend to a desirable height.

55 Mounted on top of the post is a legend bearing sign 12 held in a frame 13 carried rigidly by a flanged plug 14 secured within the post forming an ornamental cap, the sign facing the direction of approaching traffic.

60 Rigidly secured on the post, near its upper end is a ring 15 having a sinuous upper edge presenting at its front and rear diametrically opposed elevations 16, curved to blend smoothly into depressions 17 at the side edges of the ring and constituting a double inclined cam for purposes which later will be seen.

65 The gates are each constructed of a single tube bent to present a horizontal top bar 18—18' curved at its outer end to merge into an outwardly inclined strut member 19—19' curved at the bottom to merge into another horizontal bar 20—20' parallel with the bar 18—18'.

70 Fixed on the bar 18—18' is a T 21—21', a similar T 22—22' being secured on the lower bar, the center openings of the T's being directed towards each other and set rigidly in these openings are upright tubular bars 23—23'.

75 Secured to the bar 23 near its upper end is a ring 24 integrally connected with a band 25 loosely encircling the post 11 and at a point well above the bottom of the bar 23 is a similar ring 26 connecting with a band 27.

80 On the opposite bar 23' a ring 24' is fixed, its connected band 25' encircling the post 11 at a spaced distance below the band 25. Similarly another ring 26' fixed on the bar 23' at its lower portion, carries a band 27' encircling the post well below the band 27 to permit relative movement, these rings and bands constituting hinges.

85 Carried at the inner ends of the bars 18—18' are rolls or circular plugs 28—28' resting on the curved cam ring 15, and in a similar manner screw plugs 29—29' are adjustable on the inner ends of the bars 20—20', these plugs presenting curved faces to contact the post 11.

and may also rest upon a collar 30 fixed on the post above the block 10.

From the foregoing it will be understood that each of the gates is free to swing on the axis of the post without interference, being held freely but firmly by the pairs of hinge elements 24-25, adjusted by the plugs 29.

It will also be apparent that due to the weight of each gate the rolls 28-28' will seek the depressions 17 of the support ring and by reason of gravity remain normally extended oppositely outward; however should either of the gates be struck a blow or be pressed in either direction, the rolls 28-28' will ascend the inclined portions of the track ring, only to drop again by gravity when pressure is removed, thus acting in a fully automatic manner and will continue to so operate irrespective of weather conditions, dust or rust, indefinitely.

Thus in case either gate should be struck by a passing vehicle inadvertently, or leaned against, immediate recovery takes place and as the foundation block 10 is large and high enough to ward off the wheels of a passing vehicle, no material damage is caused the gate structure under the most adverse circumstances.

In addition plates 30-30' may be attached to the gates, preferably on the upper portions of the elements 19-19' and set in these plates are a plurality of brilliants 31 which may be of various colors and adapted to reflect the lights from an approaching vehicle, thus constituting an effective lighting means, which they are in practice, but it is obvious that another type of lighting means may be substituted and it is within the possibilities of the invention to attach metal plates to the bars 18-20 should the skeleton structure described not be regarded as sufficient.

From the foregoing it will be seen that a simple device for this purpose has been disclosed in the preferred form of its embodiment, but it is not desired to restrict the details to the exact construction shown, it being obvious that changes, not involving the exercise of invention, may be made without conflicting with the scope of the appended claims.

Having thus described the invention, what is claimed as new and desired to secure by Letters Patent, is:

1. A traffic barrier comprising a permanently fixed post, normally opposed gates independently hinged to said post to swing in either direction, and a single means completely encircling the upper part of said post to return both of said gates to diametrically opposed position after operation.

2. A traffic barrier comprising a fixed post, gates yieldably hinged to the post to normally extend in diametrically opposite directions, a cam surrounding the upper portion of said post common to both gates, and

rolls on said gates seated on said cam to return said gates to normal after yielding.

3. A traffic barrier comprising a rigid block, an upright post fixed therein, a pair of gates each independently hinged to said post, cooperative means fixedly surrounding said post to cause said gates to normally extend in diametrically opposed relation, and a cam concentrically mounted on the upper portion of said post to automatically return said gates to normal position after actuation.

4. A traffic barrier comprising a rigid post, a ring fixed to encircle said post at its upper portion, said ring having two alternating raised and lowered cam surfaces on its upper edge, gates hinged to said post to swing upon their axes independently, rolls carried by said gates to seat on said cam whereby the gates are actuated by gravity to assume diametrically opposed positions and adjustable plugs set in the lower members of said gates to contact said post.

5. A traffic barrier comprising a post, skeleton gates having inreaching upper and lower ends provided with rolls, bars connecting between said ends, pairs of hinges fixed on said bars to engage said post, said hinge pairs being in different horizontal planes, and a cam fixed to encircle said post having double undulating surfaces on which certain of said rolls are seated by gravity, whereby the gates are normally held in the path of traffic.

In testimony whereof I affix my signature.

ABRAHAM SPRUNG.
